210,158

COMBINATION CHAIN LOCK AND ALARM FOR DOORS

Felix Gilbert, New York, N.Y., assignor to General
Alarm Corporation, New York, N.Y., a corporation of Delaware

Filed Nov. 23, 1966, Ser. No. 4,796

Term of patent 14 years

(Cl. D50—5)

FIG. 1 is a front elevational view of a combination chain lock and alarm for doors embodying my new design;

FIG. 2 is a left side elevational view of the combination chain lock and alarm for doors illustrated in FIG. 1;

FIG. 3 is a right side elevational view of the combination chain lock and alarm for doors illustrated in FIG. 1;

FIG. 4 is a top plan view of the combination chain lock and alarm for doors illustrated in the previous figures; and

FIG. 5 is a cross-sectional view taken along the lines 5-5 of FIG. 1.

The chain has been shown broken away for convenience of illustration.

I claim:

The ornamental design for a combination chain lock and alarm for doors, as shown and described.

References Cited

UNITED STATES PATENTS

1,377,939 5/1921 Sundel ----- 340—283

FOREIGN PATENTS

636,985 5/1950 Great Britain.

OTHER REFERENCES

Hardware Age, Dec. 13, 1962, p. 39, top of page,
Security latch.

WALLACE R. BURKE, Primary Examiner.

WILLIAM WERTMAN, Assistant Examiner.